FILLING STATION OR THE LIKE

Otto A. Kuhler, Park County, Colo.

Application September 13, 1954, Serial No. 32,254

Term of patent 3½ years

(Cl. D13—1)

Fig. 1.

Fig. 1 is a perspective view of a filling station embodying my new design; and

Fig. 2 is a rear perspective view taken from the opposite side of the filling station as shown in Fig. 1.

I claim:

The ornamental design for a filling station or the like, as shown.
